COMBINED COVER AND LEVER-OPERATED CLAMPING RING FOR DRUMS

William F. Punte, Chicago, Ill., assignor to Continental Can Company, Inc., New York, N. Y., a corporation of New York

Application November 9, 1953, Serial No. 390,783

8 Claims. (Cl. 292—256.69)

The following specification is a detailed description of novel improvements in a combined cover and lever-operated clamping ring for drums. The drums for which the invention has been designed are metal or fiber board containers having an open end which is adapted to receive a liquid-proof closure or cover. It is common practice to apply a closure to the filled drum after which a clamping ring is applied around the cover in order to hold it in sealed position during storage and transportation. When it is intended to open the drum, some means must be provided for releasing the clamping ring and thereafter unsealing the cover. Usually it is necessary to unseal the cover as a separate operation after the clamping ring has been released and removed.

The present invention is intended to provide broadly speaking, a unitary or combined cover and clamping ring. The ring is fitted around the drum at the same time the cover is applied. Means are provided to effect rapid closing of the clamping ring with consequent sealing of the cover. In opening the drum, a reverse movement provides for rapid or snap-action release of the clamp, leaving the ring in position for advantageous manipulation in unsealing the cover proper.

One of the objects of my invention is to provide an efficiently unitary cover and clamping ring.

Another object of my invention is to provide novel means for effecting the clamping of the ring.

A still further object of my invention is to provide positive means for rapidly unclamping or releasing the ring with a snap-action.

An additional object is to provide a ring which may be operated either to clamp the cover or to be unclamped without the use of separate operating tools, but solely by manipulation of the parts carried by the ring.

Among the objects of the invention is included the provision in a clamping ring of means for positively latching it in closed position.

As indicating the novel features of the invention I have, by way of example, illustrated the preferred form in the accompanying drawings in which

Fig. 1 is a side elevation of the cover and ring in clamping position, parts being shown in vertical section;

Fig. 2 is a fragmentary top plan view;

Fig. 3 is a fragmentary horizontal section of the clamping ring on the line 3—3 of Fig. 1;

Fig. 4 is a partial side elevation of the clamping ring with the ends separated;

Fig. 5 is a fragmentary horizontal section of the clamping ring on the line 5—5 of Fig. 4 with the lever in the opposite position from line 3—3 of Fig. 1;

Fig. 6 is an exploded side elevation of the ends of the clamping ring.

Fig. 7 is a side elevation of the locking cam;

Fig. 8 is a plan view of the same;

Fig. 9 is a side elevation with parts broken away of the clamping means partly closed; and

2

Fig. 10 is a fragmentary vertical cross-section of a modified form of clamping ring.

Briefly, the novel features include a cover having an adjustable but unitary clamping ring both being applied and removed from the drum together. The cover is held in place for constricting the ring by mechanical means. These means draw the ends of the ring together into overlapping relation and the operating means are then latched in place against accidental release.

10 Cam action is utilized in the closing movement. It is also a material factor in providing for quick snap-action in unclamping the ring. The ring is then free to be lifted over the end of the drum with the cover and thus unseal the latter from the drum.

15 The invention is shown as applied to a drum 11. This may be either of sheet metal or a composite article of a drum having fiber side walls and a metal chime at the open end. The side wall of the drum 11 has an inner curl 12. A groove 13 extends around the drum spaced 20 from the curl 12 and is useful in positioning and retaining the cover in sealed position. The cover 14 consists of a sheet metal disk suitably grooved for reinforcement. The edge of the cover has a groove 15, on the lower side 25 of which is a rib 16. Above the groove the cover ends in a lip 17.

A locking band 18 is held in the groove 15 between the rib 16 and lip 17 at all times. This is accomplished by providing an upper flange 19 extending from the left end of the band 18, as shown in Fig. 6 to within a short distance of the right end. This flange 19 has a sliding fit in the groove 15 over the greater portion of the circumference of the cover 14.

30 A lower flange 20, also part of the locking band 18, is received opposite the groove 13 of the drum and in the clamping operation is constricted to lie within the groove, thus drawing down the cover into sealing position.

The left end 21 of the band 18 as shown in Fig. 6, is plain with the exception that it is provided with a hole 22 to receive a rivet 23. The right end 24 of the band 35 40 20 has an irregularly shaped opening 25. The opening or aperture 25 has longitudinal edge 26 parallel to the lower edge of the band.

The aperture 25 also has a transverse straight wall or edge 27 at right angles to the inner end of the edge 26. An arcuate edge 28 connects the outer or free ends of the edges 26 and 27. The edges 26, 27 and 23 form bearing surfaces against which the operating cam rests.

50 The operating means for constricting the ends of the clamping ring comprises a lever pivoted on the rivet 23 on the left end of the band 18 and carrying two irregularly shaped plates, one of which serves as a cam (see Fig. 3).

The back plate 29 is rectangular with circular ends. It is longer than the side edge of the opening 25 and is carried on the rivet 23 and spaces the two ends of the band.

55 A cam plate 30 is provided of the same general rectangular form as back plate 29. The cam plate 30 is fitted to the front face of back plate 29, as shown in Fig. 7. The overall length of cam plate 30 is the same as the edges 26 and 27, as indicated in Fig. 9. Both plates 29 and 30 are fastened together on the rivet 23 on end 21 of the band and also by a floating rivet 31.

60 The cam plate 30 rests in the opening 25. By resting one circular end in the juncture between the edges 26 and 27, the opposite curved end will travel along the arcuate edge 28 between positions parallel to the edges 26 and 27. When the plate 30 moves from parallelism with the edge 26 to parallelism with the transverse edge 27, the right end 24 of the band is free to move

to the right, while the lower end of the plate 30 travels to the left of the longitudinal edge 26 and the opposite end moves transversely of the band until the plate has completed a movement of 180 degrees in a clockwise direction. Since the plates 29 and 30 are held by the rivet 23, in definite position with respect to the left end 21 of the band 18, this results in an expanding movement in which the right end 24 of the band moves to the right in Fig. 9 by a distance equal to the line of centers between the rivet 23 and the rivet 31.

The means for rotating the cam plate 30 consists of a lever 32. This lever is held at one point by the rivet 23 and is also attached firmly to plates 29 and 30 by means of rivet 31. One end 33 of the lever 32 is circular in form and substantially covers the opening 25 in the right end 24 of locking band 18. The through-rivet 23 fastens the lever and plates together. It also passes through the left end 21 of the band and is loosely pivoted in the hole 22.

A finger hold 34 forms the free end of the lever 32 and is slightly offset for clearance, as shown in Fig. 5. The lever 32 has an inwardly raised projection or button 35 which fits in a depression 36 on the lower left hand corner of the right end of the band when the lever is extended to the left in the clamping operation. The lever is therefore latched against inadvertent dislodgment.

In this position the cam plate 30 extends to the left of the through-rivet 23 and holds the two ends 21, 24 of the locking band in position of maximum overlap and constriction. By springing the finger hold 34 outwardly, the projection 35 is lifted out of the depression 36 and the finger hold may then be given a partial rotation of 180 degrees around the through-rivet 23. This movement relaxes the tension on the ends of the band 18 and allows them to separate. In the final movement the cam plate 30 gives a quick and maximum travel for the right end 24 by which the locking ring is sprung away from the side wall of the drum. At the same time the upper flange 19 moves outwardly in the groove 15 of the cover, without however, being disengaged from the groove.

The cover and the locking band remain associated in all positions of use. When they are applied over the open end of the drum, with the attached lever extending to the right, as shown in Figs. 4 and 5, the locking band slips readily over the side wall of the drum. Rotation of the lever up and to the left into the position shown in Figs. 1 and 3, causes the cam plate 30 to travel along the arcuate edge 28 to the left as shown in Fig. 9. When the line of centers 23, 31 is parallel to the lower edge of the band, the ends 21 and 24 overlap to the maximum amount and the band is constricted. The final movement latches the projection 35 in the depression 36.

The band is therefore clamped securely over the side wall of the drum. In this operation, the flange 19 fits closer within the groove 15, the flange 20 is pulled into the groove 13, and thus seals the cover 14 in place.

The unclamping operation is effected by movement of the lever 32 from the position shown in Fig. 1 upwardly and over into the horizontal position shown in Fig. 4. This relieves the compression between the ends 21 and 24, allowing them to expand. The band 18 is thus spread, although the upper flange is still held within the groove 15. The spreading operation permits the lower flange 20 of the band to clear the side wall of the drum.

The clamping band can then be readily lifted to unseal the cover from the end of the drum.

Fig. 10 illustrates the invention as applied to a cover having a flared compressible skirt. The cover 14 has an integral depending skirt 37 which has been slotted to allow for a normal flare. In the sealing operation the cover rests on the upper run of the container and

the resilient flared skirt compressed by the band 18. The band has the upper flange 19 sufficiently long to overlie the edge of the cover in the extended or open position. The lower flange 20 is clear of the side wall of the drum in the open position but fits closely into the groove 13 when compressed. In both positions the flange 20 holds the lower edge of the slotted skirt.

Once assembled, the combined cover and locking band are manipulated as one article. The band with the flared skirt is fitted loosely around the drum and the ends of the band constricted as shown in Figs. 4, 9, and 1. This causes the lower flange to engage in the groove 13 and at the same time compress the skirt to a fit close around the drum.

While the preferred form of my invention has been illustrated and described for the purpose of example, minor changes in material, proportions and arrangement of the parts can be carried out without departing from the essential features of the invention as defined in the following claims.

What I claim is:

1. A combined cover and captive locking band for a container comprising a cover portion, a locking band having overlapping ends and a flange adjustable around the cover, the outer end of the band having an aperture forming a plurality of angularly disposed bearing surfaces, a pivot journaled in the inner end of the band, a plate on the pivot underlying the aperture in the outer end of the band, a cam on the pivot and in the said aperture, a lever on the pivot overlying the outer end of the band and a rivet for holding the lever, the plate and the cam together for simultaneous rotation.

2. A combined cover and captive locking band for a container comprising a cover portion having a peripheral groove, a locking band having overlapping ends and a flange adjustably held in said groove, the outer end of the band having an aperture forming a plurality of angularly disposed bearing surfaces, a pivot journaled in the inner end of the band, a plate on the pivot underlying the aperture in the outer end of the band, a cam on the pivot and in the said aperture, a lever on the pivot overlying the outer end of the band and a rivet for holding the lever, the plate and the cam together for simultaneous rotation.

3. A combined cover and captive locking band for a container comprising a cover portion, a locking band having overlapping ends and a flange adjustable around the cover, the outer end of the band having an aperture with two right-angular edges connected by an arcuate edge, a pivot journaled in the inner end of the band, a plate on the pivot underlying the aperture in the outer end of the band, a cam on the pivot and in the said aperture, a lever on the pivot overlying the outer end of the band and a rivet for holding the lever, the plate and the cam together for simultaneous rotation.

4. A combined cover and captive locking band for a container comprising a cover portion having a peripheral groove, a locking band having overlapping ends, and a flange adjustably held in said groove, the outer end of the band having an aperture with two right-angular edges connected by an arcuate edge, a pivot journaled in the inner end of the band, a plate on the pivot underlying the aperture in the outer end of the band, a cam on the pivot and in the said aperture, a lever on the pivot overlying the outer end of the band and a rivet for holding the lever, the plate and the cam together for simultaneous rotation.

5. A combined cover and captive locking band for a container comprising a cover portion, a locking band having overlapping ends and a flange adjustable around the cover, the outer end of the band having an aperture with one longitudinal bearing edge, one transverse bearing edge and an arcuate edge connecting said longitudinal and transverse bearing edges, a pivot journaled in the inner end of the band, a plate on the pivot under-

70

75

lying the aperture in the outer end of the band, a cam on the pivot, said cam having two spaced ends each adapted to bear against an edge of the aperture, a lever on the pivot overlying the outer end of the band and a rivet for holding the lever, the plate and the cam together for simultaneous rotation.

6. A combined cover and captive locking band for a container comprising a cover portion, a locking band having overlapping ends and upper and lower flanges, the upper flange adjustable around the cover, and the lower flange movable into engagement with the sidewall of the drum, the outer end of the band having an aperture forming a plurality of angularly disposed bearing surfaces, a pivot journaled in the inner end of the band, a cam on the pivot and in said aperture, a lever on the pivot overlying the outer end of the band and a fastening for holding the lever and the cam together for simultaneous rotation.

7. A combined cover and captive locking band for a container comprising a cover portion, a locking band having overlapping ends and a flange adjustable around the cover, the outer end of the band having an aperture forming a plurality of angularly disposed bearing surfaces, a pivot journaled in the inner end of the band,

a cam on the pivot and in the said aperture, a lever on the pivot overlying the outer end of the band and a fastening for holding the lever and the cam together for simultaneous rotation, the bearing surfaces being so formed that the cam presses against a surface during the latter portion of the unlocking movement of the lever.

8. A combined cover and captive locking band for a container comprising a cover portion, a locking band having overlapping ends and a flange adjustable around the cover, the outer end of the band having an aperture forming a plurality of angularly disposed bearing surfaces, a pivot journaled in the inner end of the band, a cam on the pivot and in the said aperture, a lever on the pivot overlying the outer end of the band and a fastening for holding the lever and the cam together for simultaneous rotation and interengaging latch means on the lever and the outer end of the band.
